UNITED STATES PATENT OFFICE.

JAMES J. MCKAY, OF BALTIMORE, MARYLAND.

DESIGN FOR A COMBINED PAPER WEIGHT AND PICTURE HOLDER.

Application filed August 6, 1924. Serial No. 10,395. Term of patent 14 years.

To all whom it may concern:

Be it known that I, JAMES J. MCKAY, a citizen of the United States, residing in the city of Baltimore and State of Maryland, have invented a new, original, and ornamental Design for Combined Paper Weight and Picture Holder, of which the following is a specification, reference being had to the accompanying drawing, forming part thereof.

The figure is a perspective view of a combined paper weight and picture holder showing my new design.

I claim:

An ornamental design for a combined paper weight and picture holder as shown.

JAMES J. MCKAY.
